UNITED STATES PATENT OFFICE

PAUL S. HAUTON, OF ATLANTA, GEORGIA

DESIGN FOR A MECHANICAL PENCIL

Application filed April 27, 1932. Serial No. 43,631. Term of patent 14 years.

To all whom it may concern:

Be it known that I, PAUL S. HAUTON, a citizen of the United States, residing at 423 Houston Street, in the city of Atlanta, in the county of Fulton and State of Georgia, have invented a new, original, and ornamental Design for Mechanical Pencils, of which the following is a specification, refer-

ence being had to the accompanying drawing, forming part thereof.

The figure is a plan view of a mechanical pencil, showing my new design.

I claim:

The ornamental design for a mechanical pencil, as shown.

PAUL S. HAUTON.
